UNITED STATES PATENT OFFICE.

ALEXANDER T. BALLANTINE, OF CLEVELAND, OHIO, ASSIGNOR TO THE DOMESTIFROID COMPANY, OF SAME PLACE.

OILING DEVICE.

SPECIFICATION forming part of Letters Patent No. 578,961, dated March 16, 1897.

Application filed September 19, 1895. Renewed January 29, 1897. Serial No. 621,222. (No model.)

To all whom it may concern:

Be it known that I, ALEXANDER T. BALLANTINE, of Cleveland, in the county of Cuyahoga and State of Ohio, have invented a new and 5 useful Improvement in Oiling Devices, of which the following is a specification.

My invention consists in an improved device for automatically oiling the pistons of an ammonia-pump, hereinafter fully described 10 and claimed.

Figure 1 is a side elevation, with the pump in section, of my improved device. Fig. 2 is a side elevation of the valve mechanism. Fig. 3 is a vertical central section thereof on line x, 15 Fig. 2; and Fig. 4 is a detail sectional view of portions of one of the cylinders and of the casing, the piston being in elevation and the plane of section being at right angles to the plane of section of Fig. 1.

20 A represents the casing of an ammonia-pump, in which B represents the cylinders, T T the pistons, E a rock-shaft actuated by a suitable motor, and D a walking-beam whose ends are connected by connecting-rods 25 C with pistons T, all this being the same as in my Patent No. 476,358, dated June 7, 1892.

J represents a disk loosely sleeved on shaft E and provided with a set of ratchet-teeth H, with which engage a pawl i, carried on an 30 arm I, secured to the casing A to hold disk J against rotation in one direction, and another pawl h, carried on walking-beam D, to turn said disk J step by step to the right, Fig. 1. The lower part of the casing A is intended to 35 contain oil, into which the disk J dips, and by touching each piston T when at its lowest point leaves a little oil thereon, all this being substantially the same as in my pending application for patent, Serial No. 491,558, filed 40 November 21, 1893.

The invention of this present application relates to a device for maintaining the oil-level in casing A, the device described in my prior application being an ordinary float-valve. Inasmuch as the pressure in casing 45 A is comparatively small, twenty to thirty pounds, while the pressure under which the oil is delivered to said casing is ordinarily quite high, one hundred and fifty to one hundred and sixty pounds, the work imposed upon the float-valve in my former application

is quite severe, and the mechanism in this application is designed to relieve the float from this work by causing the valve to be opened and closed positively by a moving part of the 55 pump, while the float simply throws the valve mechanism in and out of contact with the moving part by which it is actuated.

K represents an oil-inlet pipe leading into the bottom of casing A, the other end of which 60 is connected with an oil-separator, in which the oil and ammonia separate, and which is under the pressure of the compression side of the machine, which often runs to one hundred and sixty pounds.

65 Q represents a plug-valve in a casing L on the upper end of pipe K, the opening through said valve being represented by g.

J represents a stem connected with plug Q, adapted to work in a slot R in casing L, so as 70 to throw opening g in or out of communication with a small passage k, connecting with pipe K.

P represents a bar through which is formed a hole m to loosely embrace stem j, and at 75 one end bar P is connected with a lever M, which is pivoted on a pin N, secured in the end of casing L, and said lever M is slotted, so as to be capable of both swinging on its pivot M and of rising and falling thereon. At the 80 upper end lever M has a shoulder a and at the lower end a shoulder b.

d represents a float adapted to rise and fall with the varying oil-level in casing A, and connected with one end of a rod e, which passes 85 under bar P and is pivoted at f to a lug n on casing L. I preferably curve the rod e where it passes under bar P in order to make it clear at the casing L, but of course it can be fulcrumed at a higher point and be straight, if desired. 90

F represents a tappet on walking-beam D, so placed that when lever M is at its lowest position, as shown in Fig. 1, its line of travel as said walking-beam swings will be above the shoulder a at the top of said lever. 95

G represents a tappet secured to the end of walking-beam D and so proportioned that when lever M is at the highest point of its travel the end of said tappet G will as it is moved downward pass below the shoulder b 100 and the lever M.

The operation of my invention is as fol-

lows: When there is no oil in casing A or too little oil, the float *d* falls, dropping lever *M* to the position shown in Fig. 1. As the left-hand end of walking-beam *D* descends, the 5 end of tappet *G* strikes shoulder *b*, forcing it to the right, Fig. 1, and turning the plug *Q*, through the medium of bar *P* and stem *j*, until the opening *g* therein registers with the pipe *K*, when oil passes through the valve 10 and flows into chamber *A*. As oil rises in said chamber, float *d* rises, raising bar *P* and lever *M* until finally shoulder *a* comes in the 15 line of travel of tappet *F*, and the motion of said walking-beam throws the upper end of lever *M* to the right, thus closing the valve and checking the further flow of oil. It will be seen, therefore, that the only work which the float *d* is called upon to perform is that of raising the bar *P* and lever *M*, which are 20 small light affairs, and that the opening and closing of the valve are done by the power which drives the pump. This enables me to use a small float and light rod, and still to govern the oil-valve against very heavy pressure.

25 What I claim as my invention, and desire to secure by Letters Patent, is—

1. In combination with a pump-casing having moving mechanism therein, an oil-inlet pipe, a valve controlling said inlet-pipe, a movable lever connected with said valve, and governed by a float, and two tappets on the moving mechanism adapted respectively to move said lever in one direction when raised, and in the other direction when lowered, and to 30

thus open or close said valve, substantially 35 as shown and described.

2. In combination with a pump-casing and moving mechanism therein, two tappets on said mechanism traveling in different paths, an oil-inlet pipe, a valve controlling said inlet-pipe, lever movably connected with said valve, shorter than the distance between the paths of said tappets, and a float operated by the oil in the pump-casing to carry said lever into the path of one tappet when the oil-level 40 rises to a certain height, and into the path of the other tappet when the oil-level falls, whereby the valve is opened and closed by said tappets, substantially as shown and described. 45

50 3. In combination with a vessel and moving mechanism therein, two tappets moving in different paths, a valve controlling an inlet-pipe in said vessel, an actuating-lever movably connected with said valve, a float and a pivoted lever connected with said float and governing the position of said valve-lever, substantially as shown and described.

4. In combination with casing *A*, walking-beam *D*, having tappets *F* and *G*, inlet-pipe 60 *K*, valve *Q*, lever *M* movably connected with valve *Q*, float *d* and pivoted rod *e* connected to lever *M*, substantially as shown and described.

ALEXANDER T. BALLANTINE.
